V. BENDIX

BRAKE SHOE

Filed June 20, 1927

FIG. 1

FIG. 2

FIG. 4

FIG. 3

INVENTOR
VINCENT BENDIX

BY

Jn. W. McConkey
ATTORNEY

UNITED STATES PATENT OFFICE.

VINCENT BENDIX, OF CHICAGO, ILLINOIS, ASSIGNOR TO BENDIX BRAKE COMPANY, OF SOUTH BEND, INDIANA, A CORPORATION OF ILLINOIS.

BRAKE SHOE.

Application filed June 20, 1927. Serial No. 200,041.

This invention relates to brake shoes, and is illustrated as embodied in shoes for an internal expanding automobile brake. An object of the invention is to provide a light 5 but strong shoe, by pressing out in one piece two integrally-connected sections or stampings, which are afterwards folded upon each other, preferably along a chord of the shoe.

The sections are shown as being L-shaped 10 in section, and folded upon each other back to back, so that they provide a double-thickness stiffening web. This web may be cut away, for example when cutting out the blank, as described below, in such a manner 15 as to lighten the shoe without sacrificing its strength.

The above and other objects and features 20 of the invention, including various novel and desirable structural details, will be apparent from the following description of the 25 illustrative embodiments shown in the accompanying drawing, in which:

Figure 1 is a side elevation of one form of shoe, finished except for attaching the brake 30 lining;

Figure 2 is a top plan view of the shoe shown in Figure 1;

Figure 3 is a section through the shoe on the line 3—3 of Figure 1; and

Figures 4 and 5 are side elevations of 35 modified forms of shoes embodying my invention.

The shoe illustrated in Figures 1-3 is a secondary shoe for a three-shoe brake of the 40 type described in Patent No. 1,567,716, granted Bendix Brake Company on December 29, 1925, on application of A. Y. Dodge.

This novel shoe includes two sections or 45 stampings, each including an arcuate flange 10 to which the brake lining may be attached, the two flanges 10 thus forming the friction face of the shoe.

Each section also includes a portion or 50 web 12, the two web portions being integrally connected at 14 along their inner edges, at opposite ends of the shoe, along a chord of the shoe. Thus in manufacturing 55 the shoe, the two sections are folded together along a line passing through and connecting the portions 14, the two web portions 12 then being spot-welded or riveted or otherwise secured together to form a double-thickness stiffening web.

Bushings 16 and 18 may be pressed into

openings in this web, for the anchor pivot 55 and for the pivot connecting the secondary shoe to a primary shoe which operates it.

The shoe of Figure 4 differs from that of Figures 1-3 in that the two ends are alike, these ends afterwards being suitably formed, 60 or provided with extra fittings of any desired character, to permit the shoe to be used in any brake for which it may be adapted. The shoe of Figure 5 has the fold extending continuously at 20 along its inner edge, on 65 a chord of the shoe, merely having openings 22 to lighten it.

While several illustrative embodiments have been described in detail, it is not my intention to limit the scope of the invention 70 to those particular embodiments, or otherwise than by the terms of the appended claims.

I claim:

1. An arcuate brake shoe comprising two 75 integrally-connected sections folded upon each other along a chord of the shoe.

2. An arcuate brake shoe comprising two integrally-connected L-shaped sections folded upon each other back to back along 80 a chord of the shoe.

3. An arcuate brake shoe comprising two integrally-connected sections folded upon each other along a chord of the shoe to form 85 a double-thickness web.

4. An arcuate brake shoe comprising two integrally-connected sections folded upon each other along a chord of the shoe to form a double-thickness web which is cut away to lighten it.

5. An arcuate brake shoe comprising two integrally-connected sections folded upon each other along a chord of the shoe to form a double-thickness web cut away from said chord along an arc generally paralleling 95 the friction face of the shoe.

6. An arcuate brake shoe comprising two sections integrally connected at spaced points and cut away between said points and folded upon each other along a line passing 100 through said points.

7. An arcuate brake shoe comprising two sections integrally connected at opposite ends of the shoe and folded upon each other.

In testimony whereof, I have hereunto 105 signed my name.

VINCENT BENDIX.
